UNITED STATES PATENT OFFICE.

CHARLES W. WIPFLER, OF DETROIT, MICHIGAN.

REGISTER.

No. 911,102.

Specification of Letters Patent.

Patented Feb. 2, 1909.

Application filed April 6, 1908. Serial No. 425,319.

To all whom it may concern:

Be it known that I, CHARLES W. WIPFLER, a citizen of the United States of America, residing at Detroit, in the county of Wayne and State of Michigan, have invented certain new and useful Improvements in Registers, of which the following is a specification, reference being had therein to the accompanying drawings.

10 This invention relates to registers for hot air furnaces and the like and more especially to means for operating the shutter whereby it is held locked in any desired position.

The invention consists in the matters hereinafter set forth, and more particularly pointed out in the appended claims.

In the drawings, Figure 1 is a view in front elevation of a register embodying features of the invention. Fig. 2 is a view in 20 vertical section of the register. Fig. 3 is an enlarged view in detail of a shutter and shutter lock. Fig. 4 is a view in detail of the lock removed from the register.

Referring to the drawings, 1 indicates a 25 rectangular frame adapted to form the casing of an opening in a wall communicating with a hot air pipe or flue, and provided with a face or grille plate 2. A shutter frame 4 is formed or secured on the back of the casing 30 by screws 3 or the like and a shutter 5 of suitable material is pivoted therein on a horizontal bar 6 at a point below its upper edge, so as to close inwardly against strips or stops 7 which are preferably oblique to the face plate 35 so as to be slightly inclined toward the flue when the register is set. In the preferred form of construction, the shutter is a sheet metal plate folded on itself along its upper edge with the margin 8 of the downturned part being reverted to form a tubular bearing 40 for the rod.

A lock 9 which is in form a disk, is secured by a stud 10 on a lug 11 on the rear of the grille 2 to oscillate in substantially the horizontal plane of the shutter pivot. A substantially radial cam arm 12 on the disk has a rounded outer end rocking and sliding against the shutter above its pivot axis, while a second dependent radial cam arm 13 has an 45 end rocking and sliding on the shutter below its pivot axis. An operating arm 14 on the disk extends through a slot 15 of the face plate.

In operation, swinging the operating arm 50 rocks the shutter in or out, the two cam arms

being in simultaneous contact with the shutter and holding it at any desired angle; adjustment of the slightest amount is possible, the device being self-locking in any position.

What I claim as my invention is:—

1. A register for a hot air furnace and the like comprising an upright frame, a shutter pivoted therein between its ends to swing on a horizontal axis, and an operating lock oscillatory in a plane transverse to the shutter, 60 adapted to bear outwardly against the shutter above its pivot axis when turned in one direction and to bear outwardly against it below the pivot axis when turned in the other direction.

2. A register for a hot air furnace and the like comprising an upright frame, a shutter pivoted therein between its ends to swing on a horizontal axis, and an operating lock oscillatory in substantially the horizontal 75 plane of the shutter pivot axis, adapted to bear outwardly against the shutter above its pivot axis when turned in one direction and to bear outwardly against it below the pivot axis when turned in the other direction.

3. A register for a hot air furnace and the like comprising an upright rectangular frame, a shutter of sheet metal folded on itself along its upper edge, the lower margin of the downturned part being bent into a tubular bearing, a horizontal pivot rod in the frame on which the bearing swings, and an operating lock oscillatory in a plane transverse to the shutter, adapted to bear outwardly against the shutter above its pivot 85 axis when turned in one direction and to bear outwardly against it below the pivot axis when turned in the other direction.

4. A register for a hot air furnace and the like comprising an upright frame, a shutter pivoted therein between its ends to swing on a horizontal axis, and an operating lock consisting of a disk pivoted to turn in substantially the horizontal plane of the pivot axis, a cam arm thereon bearing against the adjacent face of the shutter above its pivot axis, a second cam arm thereon bearing against the adjacent face of the shutter below its pivot axis, and an operating arm extending forwardly from the disk.

5. A register for a hot air furnace and the like comprising an upright rectangular frame, a shutter of sheet metal folded on itself along its upper edge, the lower margin of the downturned part being bent into a tu- 110

bular bearing, a horizontal pivot rod in the frame on which the bearing swings, and an operating lock consisting of a disk pivoted to turn in substantially the horizontal plane of the pivot axis, a cam arm thereon bearing against the adjacent face of the shutter above its pivot axis, a second cam arm thereon bearing against the adjacent face of the shutter below its pivot axis, and an operating arm extending forwardly from the disk.

6. A register for a hot air furnace and the like comprising an upright frame, a shutter pivoted therein between its ends to swing on a horizontal axis, and an operating lock consisting of a disk pivoted to turn in substantially the horizontal plane of the pivot axis, a cam arm thereon bearing against the adjacent face of the shutter above its pivot axis, a second cam arm thereon bearing against the adjacent face of the shutter below its pivot axis, and an operating arm extending

forwardly from the disk, said operating lock being integrally formed in one piece.

7. A register for a hot air furnace and the like consisting of an upright rectangular casing, a grille removably secured therein, a shutter frame at the rear side of the casing, a shutter pivoted therein between its ends to swing on a horizontal axis, and an operating lock oscillatory in a plane transverse to the shutter adapted to bear outwardly against the shutter above its pivot axis when turned in one direction and to bear outwardly against it below the pivot axis when turned in the other direction.

In testimony whereof I affix my signature in presence of two witnesses.

CHARLES W. WIPFLER.
